SAMUEL BENSON, OF CENTRALIA, ILLINOIS, ASSIGNOR TO HIMSELF, JAMES BENSON, AND JOHN F. BENSON, OF THE SAME PLACE.

Letters Patent No. 79,528, dated June 30, 1868.

IMPROVEMENT IN REGULATING-DEVICE OF MILLSTONES.

The Schedule referred to in these Letters Patent and making part of the same.

TO ALL WHOM IT MAY CONCERN:

Be it known that I, SAMUEL BENSON, of Centralia, in the county of Marion, and State of Illinois, have invented a new and useful Improvement in Springs for Regulating the Motion of Millstones; and I do hereby declare that the following is a full, clear, and exact description thereof, which will enable others skilled in the art to make and use the same, reference being had to the accompanying drawings, forming part of this specification, in which—

Figure 1 is a central vertical section of a mill-spindle, with my improved compensating-springs and trundle-head attached.

Figure 2, a horizontal section of the springs taken in the line $z z$, fig. 1.

Similar letters of reference indicate like parts.

The object of this invention is to provide the means of perfectly compensating for the check of the engine while passing dead-centres, and equalizing the motion of millstones. This object is accomplished by means of spiral springs enclosed in disks, or a circular case set upon the mill-spindle in connection with the trundle-head, in such manner that the springs are contracted by the action of the motive-power when it exerts its greatest force in the more rapid part of the revolutions of the driving-shaft, and are retracted or expanded when the engine passes the dead-centres, and slacks the speed of the driving-shaft, thus applying the accumulated force of the contracted springs to the propulsion of the spindle, to compensate for the loss of power and motion directly imparted by the engine, thereby effectually preventing the "backlash" of the machinery, and equalizing and steadyng the motion of the spindle and runner attached to it, as hereinafter more particularly described.

A represents a mill-spindle, on the lower end of which is keyed fast a bush or sleeve, B, which supports the trundle-head C, that is loosely hung upon it.

Above the trundle-head the lower section, D, of a disk or spring-case, is hung loosely upon the spindle A, the under side of the disk-section D being provided with lugs, a a, that set within the web of the trundle-head, and catch upon the arms or spokes b of the wheel, for the purpose of carrying the spindle by means of the upper section of the case D', which is rigidly keyed or otherwise fastened to the spindle, and is also secured to the lower section D by means of bolts in the rims or peripheries of the disks, which pass through slots in one of the sections, to allow them a limited reciprocating movement for the action of contraction and expansion in the spiral springs E E, contained within the disks or case, as hereinafter described.

The springs E E are formed in sections or segments, coiled spirally to fit in a circular hollow space formed by equal concentric grooves in the upper and lower parts of the case, and facing each other when the sections D and D' are united.

The circular groove in the lower section D is divided into two equal parts by partitions, c c, made fast and placed opposite each other, projecting so as to enter the groove in the section D', and the circular groove in the upper section D' is also divided in the same manner by partitions c' c', also made fast in it, and projecting into the groove in D.

When the upper and lower disks are put together, with their partitions set equally apart, the hollow space formed by the circular grooves in them is divided into four compartments, within which the spiral springs E E are laid.

When the springs are in this position it will be seen that they may be contracted by the bearing of the partitions in the grooves, acting as abutments against their ends when one of the disks is rotated, while the other is held fast, and consequently, that when the force which contracts the springs relaxes, they will expand, and exert a counteracting force. By this means they will operate upon the spindle A, to compensate for the loss of speed and power when the engine passes her dead-centres, and thus equalize the motion of the spindle and the millstone hung upon it.

The upper section D' is made fast to the spindle A, while the lower section D is loose on the spindle, and the trundle-head C is also loose upon the sleeve B, but when the trundle-head is turned, its arms engage the lugs *a a* on the lower section D, and thus turn it until the springs E E are contracted, and it engages the upper section D' by means of bolts in the rim, and rotates the spindle A, to which the upper section D' is made fast. The accumulated power of the contracted springs reacts when the pressure upon them relaxes, and thus a compensating power is applied to the spindle to equalize the motion.

Having described my invention, I claim as new, and desire to secure by Letters Patent—

The combination of the springs E E, the disk-sections D D', the pinion C, and the spindle A, arranged and operating substantially as and for the purpose herein described.
